UNITED STATES PATENT OFFICE.

CHARLES N. BARTON, OF INDIANAPOLIS, INDIANA, ASSIGNOR OF ONE-FOURTH TO FRED N. REYNOLDS, ONE-FOURTH TO FRED K. MURPHY, ONE-TWELFTH TO MARTHA E. DAVIS, AND ONE-TWELFTH TO MAY E. REYNOLDS, ALL OF INDIANAPOLIS, INDIANA, AND ONE-TWELFTH TO EVELYN M. DINNIN, OF NEW YORK, N. Y.

SECTIONAL JOURNAL BOX AND HUB LINER.

Application filed July 5, 1921. Serial No. 482,514.

To all whom it may concern:

Be it known that I, CHARLES N. BARTON, a citizen of the United States, residing at Indianapolis, in the county of Marion and

5 State of Indiana, have invented a new and useful Sectional Journal Box and Hub Liner, of which the following is a specification, reference being had to the accompanying drawings, and to the letters and figures of reference marked thereon.

This invention relates to liners which are designed to be removably secured to wheel hubs and journal boxes for the purpose of reducing lost motion of the journal boxes 15 longitudinally on axles or shafts, or of axles or shafts relatively to the journal boxes, the invention having reference more particularly to liners for wheel hubs and journal boxes of locomotives.

20 An object of the invention is to provide a liner of the above-mentioned character which shall be so constructed as to permit it to be applied or removed from place without necessitating the removal of a wheel or 25 a journal box from an axle or shaft on which they may be used.

Another object is to provide locomotive wheel hubs and journal boxes with liners of improved construction permitting ready 30 renewal when worn away in use to such an extent as to permit an undesirable amount of play or space between a wheel hub and journal box, and without removing the wheel axles from their customary places in 35 a locomotive.

A further object is to provide an improved sectional hub or journal box liner and means for securing the liner in place so that the liner shall be firmly and reliably held in 40 place and not be liable to be broken or damaged in use, and which may be applied either to new machinery in the factory or to machinery in which lost motion has developed in service; which liner and securing 45 appliances shall be reliable, durable and economical in use.

With the above-mentioned and other objects in view, the invention consists in a novel sectional liner having a novel holder 50 whereby to removably secure the liner to a wheel hub or a journal box; and, the invention consists also further in the novel

parts and in the combinations and arrangements of parts as hereinafter particularly described and further defined in the accompanying claims.

Referring to the drawings,—Figure 1 is an elevation of a locomotive wheel and axle and a journal box provided with the liners embraced in the invention; Fig. 2 is a fragmentary horizontal section of the wheel hub and the journal box provided with the improved liners, on an enlarged scale; Fig. 3 is a rear face view partially in section of the improved liner and its holder as preferably constructed; Fig. 4 is a rear face view of the improved liner holder and the sections of the liner separated as when about to be secured to the holder; Fig. 5 is a fragmentary rear face view of the holder 70 and the sections of the liner applied thereto and ready to be locked to the holder, portions of the liner parts being shown in section; Fig. 6 is a top plan illustrating the manner of arranging the improved liner; Fig. 7 is a rear face view of the improved liner holder, partially broken away, and the liner slightly modified as to details, portions of the liner being in section; Fig. 8 is a central section of a wheel hub and the improved liner applied thereto, the liner and its holder being on the plane of the line VIII—VIII in Fig. 7; Fig. 9 is a rear face view of the liner holder and the modified liner arranged as when being applied to or removed from the holder; Fig. 10 is a peripheral view of the improved liner as it appears before it is locked to its holder; Fig. 11 is a fragmentary section on the line XI—XI in Fig. 7; and, Fig. 12 is a fragmentary rear face view of the liner holder and the liner applied thereto and ready to be locked to the holder, portions of the parts of the liner being in section.

Similar reference characters in the various figures of the drawings indicate corresponding elements or features of construction herein referred to in detail.

In the drawings, the numeral 1 indicates the rim portion of a wheel having a hub 2 secured to an axle 3 on which a journal box 4 is supported. In common practice the journal box is close to the wheel hub and guided thereby on the axle, and the bearing

faces wear away and require liners which fill the undesirable space between the box and the hub resulting from the wearing away of the parts. When the locomotive is being built it may be supplied with the improved liners which may readily be replaced when worn away by new liners.

The inner end of the hub 2 is supplied with a holder designed to permanently retain thereon, but is not necessarily integral therewith. Preferably the holder comprises a disk-shaped plate 5 having a central aperture 6 corresponding in diameter to that of the axle, which may be inserted in the aperture before the axle is inserted into the wheel hub, and in such case the plate may be fitted tightly on the axle, as a collar. The holder plate obviously may be composed of several parts if desired to permit it to be placed on the axle at any time after the axle is secured to the wheel. The plate is placed against the inner end of the hub and essentially it is larger than the hub diametrically so as to produce a flange-like circumferential guide rib on the hub. The plate is provided with a suitable number of countersunk holes 7 receiving securing bolts 8 which extend through the hub 2. In some cases a similar holder plate 5' is likewise arranged on the side of the journal box 4 opposite to the wheel hub and secured to the box by means of bolts 9 extending through the box. Each securing bolt has a countersink head arranged in the hole 7 and a nut 11 on the end of the bolt.

Each holder plate, which when made separately from the hub and the journal box constitutes the core of the improved liner, has two shoulders 12 and 13 oppositely arranged and formed preferably by recessing a portion of the periphery of the holder plate which forms the rib for holding the wearing part or shoe portion of the liner; and in the preferred form of construction two other shoulders 14 and 15 are likewise provided on diametrically opposite portions of the plate or rib. Preferably also the peripheral portion of the plate or rib has recesses 16 and 17 therein to receive lugs.

Each liner or the wearing portion thereof that is designed to be renewed, comprises two similar segmental shoe sections having semi-circular face plates 18 and 19 respectively, and they have lateral rim portions 20 and 21 respectively that normally embrace the periphery of the holder plate or core, the rim portions having lips 22 and 23 respectively that engage the back of the holder plate while the wearing plates are close against the front face of the holder plate. One end of one of the two sections preferably has a slit 24 which separates a small portion of the rim 21 from the segment plate 19 so as to constitute a flexible tongue 25 which originally extends outwardly beyond

the arc of the rim; and likewise one end of the opposite segment is provided with a tongue 25'. The opposite ends of the rim of the segments have lugs 26 and 26' on the inner side thereof that are placed in engagement with the shoulders 12 and 14 respectively. The inner sides of the tongues have lugs 27 and 27' respectively that are forced into engagement with the shoulders 13 and 15 respectively when the tongues are forced inward to the holder plate or guide rib.

In a modified form of construction the two sections of the liner have relatively thin hinge portions 28 and 29 at one end thereof that are connected together by means of a pivot 30. The sections have also the locking lugs 26 and 27 described above. Preferably one section has a lug 31 on the inner side of the rim portion that is received in the recess 16, and the companion section has a similar lug 32 that is received in the recess 17, to assist in preventing the sections from turning on the holder or core.

When assembling the parts of the liner the sections are arranged on the holder or core and the lug 26 brought into engagement with the shoulder 12, and the lug 26' in engagement with the shoulder 14, after which the tongues 25 and 25' are pressed or otherwise forced inward until the lugs 27 and 27' engage the shoulders 13 and 15 respectively, which then securely hold the sections on the holder or liner core. In case the sections are hinged together the tongue on one of the sections is forced into place so as to securely lock the sections together on the holder.

In practical use the face plates 18 and 19 wear away and when the lost motion or play occasioned by the wear becomes excessive the tongue 25 may be forcibly broken or cut off or may be forced outward to release the lug 27 from the shoulder 13, thus permitting the sections of the liner to be removed so that new liners or shoes may be applied as before to the holders or cores of the liners.

Having thus described the invention, what is claimed as new is:—

1. A sectional journal box and hub liner including a plurality of segmental sections together comprising a continuous circular plate, each section being provided with a lateral peripheral rim portion having locking lugs at the inner side thereof, the rim portion of one of the sections having a flexible portion on which one of the lugs is fixed.

2. A sectional journal box and hub liner including a plurality of segmental sections constituting a continuous circular plate, each section being provided with a lateral curved peripheral rim portion to embrace a portion of a circular core, the rim portion having a lip on the inner side thereof to engage the back of such core, and means including a flexible tongue connected with the rim por-

tion of one of the sections and having a lug thereon to lock the sections to such core.

3. A sectional journal box and hub liner including an annular holder having a plurality of holes therein to receive securing bolts, a plurality of segmental sections together covering one of the side faces of the holder and provided with rim portions having lips to engage the opposite one of the side faces of the holder, and means co-operating to lock the rim portions of the sections to the holder to constitute a removable contact face on the holder.

15 4. The combination with a wheel hub and an axle secured to the hub, of an annular holder arranged on the end of the hub, a plurality of securing bolts extending through the hub and the holder, a segmental 20 sectional liner on the axle removably secured to the holder and covering the face thereof, the liner having a rim portion embracing the outer edge of the holder, and means co-operating to lock the rim portion 25 to the edge of the holder.

5. In a sectional journal box and hub liner, the combination of a wheel hub having a circumferential guide rib on an end thereof, the rib having lock shoulders thereon, and 30 a plurality of segmental liner sections covering the end of the hub and having lateral rim portions embracing the rib, the rim portions being provided with lips engaging the back of the rib and provided also with 35 lugs engaging the lock shoulders on the rib to secure the sections to the wheel hub.

6. In a sectional journal box and hub liner, the combination of an annular core having lock shoulders on the outer edge portion 40 thereof, and a plurality of segmental sections connected together on the core and having lugs engaging the shoulders on the core to lock the segments to the core, one of the segments being provided with a flexible 45 tongue having one of the lugs thereon to be carried on bending of the tongue to one of the shoulders.

7. In a sectional journal box and hub liner, the combination of a journal box having an annular liner holder rigidly secured to one side face thereof, the holder having lock shoulders on the outer edge portion thereof, and a plurality of segmental liner sections covering the front face of the holder and provided with rim portions embracing the 50 edge of the holder, the rim portions having lips engaging the back of the holder and having also lugs engaging the lock shoulders to secure the sections to the holder.

8. The combination with an axle, and a 60 journal box on the axle, of an annular holder arranged on one side of the journal box, a plurality of securing bolts extending through the box and the holder, a segmental 65 sectional liner on the axle removably secured to the holder and covering the face thereof, the liner being provided with a rim embracing the outer edge of the holder and having a lip engaging the back of the holder, and means co-operating with the edge of the 70 holder and also with said rim to lock the liner to the holder.

9. A sectional journal box and hub liner including an annular holder having a plurality of securing bolts connected thereto, 75 the outer edge portion of the holder being provided with oppositely facing lock shoulders, and a plurality of segmental sections covering one of the side faces of the holder and having rim portions embracing the edge 80 of the holder, the rim portions being provided with lips engaging the opposite one of the side faces of the holder and provided also with lugs engaging the lock shoulders on the holder, one of the rim portions being provided with a flexible tongue 85 having a lug thereon to be carried to or from one of the shoulders.

In testimony whereof, I affix my signature in presence of two witnesses.

CHARLES N. BARTON.
